JOURNAL BOX PACKING

Robert J. Harkenrider, Winona, Minn., assignor, by direct and mesne assignments, to Miller Lubricator Company, Winona, Minn., a corporation of Minnesota

Application July 30, 1956, Serial No. 601,011

21 Claims. (Cl. 308—243)

My invention relates to a journal box packing for railroad car journal boxes, and the like, and more particularly, to a journal box packing employing lubricant impervious core means encircled by a lubricating waste blanket means.

In recent years, railroads have been discarding conventional loose waste packing in favor of packing "packages" of uniform size and other characteristics. While these "packages" of packing have resulted in a substantial reduction of "hotbox" occurrences, experience has shown that additional improvements are necessary before the devices can be approved for unlimited interchange service.

The device disclosed in the copending application of Rudolph W. Miller and myself, Serial No. 486,766, filed February 8, 1955, the disclosure of which is incorporated by reference in interests of brevity, remedies many of the defects commonly found in lubricators of this type. Generally speaking, this device includes a waste blanket looped about a resilient core. The lubricating device herein disclosed is an improvement over the device of said copending application.

The lubricator disclosed in said copending application provides a number of improvements over conventional journal box packing packages, one of the most important being that the unit can be installed without jacking the journal box assembly. The lubricator of the present application retains the inherent advantages of the device of said copending application, while at the same time providing additional improvements.

One of the principal problems in this art is that the packing packages tend to shift to one side of the journal box and towards the edge of the bearing under the action of the rotating journal. In the lubricator of said copending application, the seam of the waste blanket is at the side of the packing and when the packing shifts to a position wherein the seamed side of the lubricator is the lower side thereof, a reduced feed results, as the seam reduces capillary action on one side of the packing, requiring that lubricant travel a relatively long path around the other side of the packing to reach the journal. As experience has shown that it is impractical at the present state of the art to prevent shifting of the lubricator, it is necessary to insure that the lubricator provides adequate lubrication even when it is in shifted position.

Accordingly, it is a principal object of my invention to provide a journal box packing of the package type designed to provide capillary feed paths of minimum length which lift a maximum amount of lubricant to the journal, regardless of the position of the lubricator in the journal box.

Another object of the invention is to provide a journal box packing that lifts lubricant in substantially a straight line between the lubricant reservoir and the journal, and thus provides a capillary feed path of minimum length.

Still another object of the invention is to provide a journal box packing which is shaped to permit excess lubricant to drain back into the lubricant reservoir during rotation of the journal, but at the same time is arranged

2

to utilize a maximum amount of this lubricant to provide a thoroughly saturated journal contacting or lubricating surface.

A further object of my invention is to provide a new design for packing packages including waste blanket means encircling resilient core means in which an improved form of core harness is employed to secure the core means to the blanket means.

Still a further object of the invention is to provide a journal box packing package which is shaped to catch a considerable portion of the surplus oil which drips from the journal and thus increases the film of oil applied to the journal during rotation, and yet which is formed to preclude the drainage of oil out of the rear of the journal box.

Yet a further object of the invention is to provide a packing package that is sufficiently flexible to be installed without jacking the box.

Other objects, uses, and advantages will become apparent upon a consideration of the following description of a preferred embodiment of my invention.

In the drawings:

Figure 1 is a transverse cross sectional view through familiar parts of a railway car journal and journal box, showing the same equipped with the packing of the present invention, with parts of the packing shown in section;

Figure 2 is a longitudinal cross sectional view through the journal box and packing package illustrated in Figure 1, the journal being shown in elevation;

Figure 3 is an exploded perspective view of the various elements comprising the packing package of Figures 1 and 2, as seen from the front or outer end thereof;

Figure 4 is a perspective view similar to that of Figure 3, but showing the parts in assembled relation and with portions broken away to expose other parts of the lubricator;

Figure 5 is a top plan view of the illustrated embodiment of my lubricator on a small scale;

Figure 6 is a plan view of the two top resilient pads of Figure 3, illustrating the configuration of their front and rear ends;

Figure 7 is a somewhat diagrammatic longitudinal cross sectional view through one end of the packing;

Figure 8 is a somewhat diagrammatic transverse cross sectional view through the center portion of the packing;

Figure 9 is a diagrammatic plan view of the waste blanket forming a part of the illustrated packing packages, with parts broken away for clarity of illustration;

Figures 10, 11, and 12 are top plan views illustrating a preferred method of assembling several of the elements comprising the illustrated embodiments of the invention;

Figure 13 is a plan view of the blank from which a modified form of core securing strap is formed;

Figure 14 is a perspective view of the strap formed from the blank illustrated in Figure 13;

Figure 15 is a view similar to that of Figure 7 illustrating the strap of Figures 13 and 14 as employed in the invention, the lower resilient pad being omitted for clarity of illustration;

Figure 16 is a view similar to that of Figure 6, illustrating in block outline form modified resilient pads employed in the lubricator of Figure 15; and

Figure 17 is an elevational view along line 17—17 of Figure 16.

General description

Referring now more particularly to Figures 1 and 2 of the drawings, reference numeral 10 generally indicates a conventional journal box on a conventional axle journal 11 with a twin lobe packing according to the present invention, generally indicated by reference numeral 12,

in place between the lower portion of the journal and the bottom of the journal box in what is commonly referred to as the oil or lubricant cellar of the journal box.

The package forming the illustrated forms of packing generally comprises (see Figure 3) a pair of attached laminated waste blankets or envelopes 14, handle means 16, a plurality of generally similar, relatively flat resilient pads 20, and a pair of H-shaped straps 22 especially adapted to securely fasten the pads 20 within and to the envelopes 14. These elements form the twin lobes of the packing and are more particularly described hereinafter.

The waste blanket

The waste blankets or envelopes of the illustrated embodiment of the invention each generally comprise a layer or layers of carded waste interlaced through carriers of fabric or sheet material, said carriers including capillary materials to raise lubricating oil to the layer of waste adjacent the journal when the package of the present invention is positioned as described above.

The envelopes 14 are shaped from blanks that may be of the type described and illustrated in my copending applications Serial No. 367,321 filed July 10, 1953, and Serial No. 419,029 filed March 26, 1954, now Patents Nos. 2,762,667 and 2,801,138, respectively, though preferably they are modified as hereinafter described. The disclosures of these copending applications are hereby incorporated by reference in the interests of brevity.

The envelope or blanket blanks of the illustrated embodiment of the invention (see Figures 7, 8, and 9) each comprise a relatively thick layer of carded waste 24 interlaced with a pair of woven carrier cloths 26 in the form of open weave laundry bag cloth in the illustrated embodiment, and a relatively thin layer of waste 28. The cloths 26 are preferably woven from strands or yarns made up of high capillary action material, such as vicara, cotton, or a mixture of both.

In accordance with the description of the aforesaid applications, the three layers are thoroughly fastened together by passing them through a hooking machine of the type, for instance, illustrated in Patent No. 2,672,673, granted March 23, 1954. As the layer or layers of waste and fabric go through the machine, they pass over a hooking plate, where they are subjected to the action of a multitude of hooked needles which reciprocate up and down. As the layers of waste and fabric go through the action of the hooked needles, many of the waste threads are caught by the hooks and pulled downwardly and looped through the remainder of the upper layer of waste, through the fabric, and the lower layer of waste, and formed into loops below the fabrics. In some instances, the waste threads will be caught near the top of the upper layer—in others, deeper into the layer—but the overall effect is to hook individual threads of waste through the mass of waste and the fabric and not only fasten those particular threads but associate threads into a blanket in which, generally speaking, all the threads are made fast against being pulled out in service.

During this hooking operation the weave of the carrier is tightened or shrunk by the interlacing of the threads which are thereby brought into intimate contact with the threads of the cloth in such a way as to promote ready transfer of oil from the carrier cloth to the waste threads. The thinner layer 28 may be formed entirely by hooking threads through the fabrics 26, or it can be in part formed by feeding a thin layer of carded waste under the carrier cloth before reaching the hooking machine or in a supplementary or preliminary hooking machine.

Moreover, the exposed surface or side of the thinner layer is preferably treated and coated with an adhesive 29 to fasten at the under side of the blanket all threads that go through to the under side of the blanket. Additionally, the adhesive forms a membrane-like barrier directly under the journal for preventing lubricating oil from draining or soaking through the blanket. It may

also be mentioned that the adhesive stabilizes the blanket in that it prevents undue stretching or bunching of the material comprising the blanket under the action of the rotating journal; thus the relatively stiff layer of adhesive provides a strengthening and reinforcing effect which materially lengthens the useful life of the packing.

The adhesive may comprise any appropriate material, many of which are known as rubber base cements. They may be used in powder form, sheet form, or liquid. Many of the so-called synthetic rubbers are appropriate, for example, Hycar latex No. 1552, type OR-25, made from petroleum by B. F. Goodrich Chemical Company, of Akron, Ohio, and thickened with a 12% ammonium casein solution. Several suitable types are specified in the aforementioned applications, and other suitable synthetic rubbers are described in "Materials Handbook" by Brady, 1944, McGraw-Hill, page 523.

Referring to Figures 10, 11, and 12, two blanks are employed in making each packing of the illustrated embodiment of the invention, each blank comprising an envelope or blanket 14. At the same time or after the blanks have been made from the sheet material manufactured as described above, they are each shaped in the form indicated in Figure 10. As shown in Figure 10, the edge 30 of each blank (which forms the front end of each blanket 14) is squared with the edges 32 that form the sides of the blanket 14. The rear edge 33 of the blank opposite edge 30 is notched or indented as at 34 and, in accordance with the present invention, the edges 32 are provided with rounded notches 36. The blank is also formed with a central perforation 38 for a purpose hereinafter made clear. In the illustrated embodiment, the perforation 38 is generally quadrilateral in configuration.

After each blank is formed, the edges of the blank are bound as indicated at 40 in Figure 11, which may be done by putting the blank through an edging or edge stitching machine. Preferably the blank is bound about the perforation 38 by suitable stitching 39. The blank is also preferably stitched longitudinally thereof where indicated in dotted lines at 41 in Figure 11 to further secure the individual threads of the waste blanket in place. Incidentally, the blanks are preferably cut from the sheet material from which they are formed in such a manner that the individual waste threads will extend transversely of the packing and also of the journal when the packing is in the position shown in Figures 1 and 2 (see Figures 3 and 4).

Each blanket or envelope 14 is provided with a handle 16 at one side thereof. The handles 16 each generally comprise a metallic end piece or buckle 42 secured to a fabric holder or strap 44 which is stitched to the envelope or blanket where indicated in Figure 11. The metallic end piece of buckle 42 is positioned adjacent the edge 30 of the blanket or envelope 14, which is the outer end thereof.

Two envelopes or blankets 14 are then positioned adjacent each other with their layers 24 in contact, and they are stitched together as and where indicated at 46 in Figure 11. It will be appreciated that this stitching is along a straight line that extends centrally of the blanks and substantially coincides with the longitudinal axis of the packing when the same is positioned as shown in Figures 1 and 2.

The resilient cores

The resilient cores of the illustrated embodiments of the invention comprise a plurality of relatively flat, resilient pads 20, each of which is composed mainly of a stack of like parallel tubes 50. Tubes 50 may be separately extruded, or may be integrally extruded in, for instance, the form illustrated, wherein each tube has a wall portion 51 in common with other tubes 50 and integral with them at adjacent corners as at 52. The individual pads 20 are of a cellular structure which is entirely integral;

the distribution of the material comprising same makes it possible to have an extremely light, springy element with a strong resistance to deforming under pressure and a high recovery upon release, even after being compressed for a long time under adverse temperature conditions. The tubes 50 are preferably made from a suitable lubricant resistant and impervious material, such as synthetic rubber.

Pads corresponding to those shown in Figure 3 can be made in a great variety of forms. Almost any polygonal form can be extruded, whether regular, irregular, right-angular, or otherwise. Of the many polygonal and generally polygonal forms which lend themselves to the application of the invention, the equilateral hexagon shown in the drawing figures is chosen because it lends itself so readily to making such pads, and it has a structure particularly adapted for this purpose. The springiness of these pads is well adapted to the needs of holding the lubricator 12 against the journal in spite of all the vibrations, presence of oil, cold, and other conditions that obtain in the journal box.

The pads illustrated, for instance, in Figure 3 are preferably of synthetic rubber and may be produced according to the teachings of my copending application Serial No. 418,442, filed March 24, 1954; said application also discloses suitable material for making the pads. The disclosure of said application is incorporated herein by reference in the interests of brevity.

As seen in Figure 6, the ends of the pads 20 may be trimmed diagonally of their lengths for a purpose hereinafter made clear. Alternately, the pad ends may be trimmed as diagrammatically indicated in Figures 16 and 17.

While the multitubular pads illustrated in Figures 3 and 16 are a preferred type of core, similarly shaped pads of sponge rubber, natural hair or fiber glass would also be satisfactory.

The pads 20 and the straps 22 are arranged generally in accordance with the invention described in the said copending application Serial No. 486,766. Generally speaking, two of the pads 20 are positioned on either side of H-strap 22 and the whole inserted and secured to a blanket 14 as hereinafter described.

The securing straps

The securing straps 22 are best illustrated more particularly in Figures 3 and 14. Each strap 22 of the embodiment of the invention illustrated in Figure 3 comprises a pair of strips 56 of a suitable fabric placed side by side and stitched together at the center and at each end of the individual straps where indicated at 58 in Figure 3. The ends of the strips 56 are bent away from each other to a position in which they are in substantial alignment, and a strip of strong, non-stretchable cloth tape or its equivalent 60 is secured to the angled ends of the strips 56, the tapes 69 being stitched to both strips 56 as shown at 62. Preferably, the area of each strap 22 adjacent its rear end (that is, for instance, the right hand side of Figure 3) is rubberized with, for instance, Hycar latex, on the inner or outer surface thereof, or both, somewhat as indicated at 64 in Figure 3. Said latex is a product of the aforementioned B. F. Goodrich Rubber Company.

It will be appreciated from Figure 3 that each strap 22 assumes a substantially H-shaped configuration in which the portions of the strips 56 that are connected together form the web 57 of the H and the normally disposed ends form the legs 59 thereof.

Also, in the illustrated embodiment, the cloth tapes 60 are of particular significance. As best seen in Figure 3, the front tapes 60 each have a generally quadrilateral configuration which respectively generally conform to the configuration of the open front or outer ends of the looped blankets while the rear tapes 60 have a six sided configuration, they being generally similar to the front 75

tapes, but including a trapezoidal flap 68. These configurations are provided to substantially close off the open ends of the looped blankets. In the illustrated embodiment of the invention, a supplementary securing strap 66 is secured to each flap 68 of rear tapes 60 by stitching 69 (see Figure 12).

Referring to Figure 12, after the pairs of blankets 14 have been stitched together as indicated in Figure 11, one end of the rear leg 59 of a securing strap 22 is secured to one side of the rear end of each blanket 41 and one end of the front leg 59 thereof is secured to the front end of said blankets in the manner indicated in Figure 12. Preferably tapes 60 are long enough to be included in this stitching so that one edge of the rear tape 60 and one end of a strip 56 are stitched to the rear side of the blanket 14, and one edge of the front tape 60 and one leg of a strip 56 are stitched to the front end of the blanket 14 (see Figure 7). Preferably, the tapes 60 and the ends of the strips 56 are secured to the blanket 14 by common stitching 70 (see Figure 7). Supplemental stitching 71 may also be employed (see Figure 12). The unattached end of each strap 66 is secured to the front end of each blanket as by stitching 73 (see Figure 12).

When straps 22 have been secured to both blankets 14, the blankets are respectively bent to position their edges 32 adjacent each other and the unfastened legs 59 are made fast to the respective blankets by stitching 70 and 71. The two pads 20 of each blanket are positioned on either side of the respective strap webs 57 and then the edges 32 of each blanket are brought together and are secured together with their edges 32 facing outwardly of the lubricator. These edges 32 may be secured together by stitching 75 and by brass staples 72 or other suitable securing means. As indicated in Figures 4 and 5, a hollow rivet 74 holds the rear edges of the respective blankets together.

As stated in the aforesaid copending application Serial No. 486,766, the reason for rubberizing the rear ends of the securing straps 22 is that when a railroad car is on an inside curve (with respect to the journal shown in Figures 1 and 2), lubricant within the package 12 will be retained therein and restrained from flowing out of the journal box over the lips 77 at the rear of the journal box (see Figure 2).

When the package embodying this invention is to be put to use, it is compressed and worked down under the journal into the position shown in Figures 1 and 2. The notches 36 and the perforations 38 of the blanket 14 are aligned with each other along the transverse axis of the lubricator by the manner in which the blankets are secured together. This permits or provides additional flexibility of the lubricator and allows the lubricator to be installed without having to jack the journal box.

Once in the position shown in Figures 1 and 2, the pads 20 comprising the resilient core of the lubricator hold the package in place and prevent it from working out of the correct position. Due to the flatness and the secure manner in which the blankets 14 are secured together, as well as the relatively flat space enclosed or encircled by each blanket, the tendency of the package to roll out from under the journal and to one side of the journal box, as distinguished from shifting bodily under the action of the journal, is eliminated. The secureness of the resilient pad fastening straps 22 also aids in providing this result.

Figures 13-17 illustrate a modified embodiment of the invention wherein the core securing strap is formed out of a single blank 90 of a suitable fabric, rather than from straps 56 and tapes 60. The blank 90 is formed with bend lines A, B, C, D, and E, forming portions 92, 94, 96, 98, 100, 102, 104, and 106 and is slit along unbroken line 108. The blank 90 is folded along the respective bend lines in the manner indicated in Figure 14 to form the securing strap 22A. Thus, the portions 96 and 104 are juxtaposed by bending the blank 90 along

the line A. The portion 92 is then bent toward portions 94 and 106 along line E, the portions 94 and 106 being bent outwardly of the respective portions 96 and 104 along lines C, to juxtapose portion 92 adjacent portions 94 and 106 with the center line 93 of portion 92 adjacent lines C; at the other end of the strap, the portion 100 is bent toward the portions 98 and 102 along line D, the portions 98 and 102 being bent outwardly of the respective portions 96 and 104 along lines B, to juxtapose portion 100 adjacent portions 98 and 102, with the center line 101 of portion 100 adjacent lines B. The respective portions of the blank 90 then may be secured together by, for instance, stitching 110. Strap 66 is secured by stitching 73 as described hereinbefore, and adhesive 64 (not shown) may be applied to the inner end of each strap 22A.

The core securing strap 22A formed from blank 90 is preferably secured to the individual blankets 14 in the manner indicated in Figure 15. As shown, the stitching 70 preferably passes through the layered portions of the strap legs 59, and in addition, supplemental stitching 71 may be employed. (see Figure 12). Preferably, the pads 20A and the strap 22A are so proportioned that the legs 59 of the strap are bent somewhat as shown in Figure 15 when the pads are in place. Moreover, the ends of the pads 20A of this embodiment are trimmed as diagrammatically indicated in Figures 16 and 17, that is, the ends of the respective pads taper toward the center of the lubricator. This relationship substantially eliminates bulging of the core securing strap legs outwardly of the lubricator when the lubricator is compressed, and securely holds the resilient pads in place.

Advantages of the invention

One of the most important features of the invention is the center capillary feed provided by the bent portions of the blankets 14, that is, the area of each along which they are secured together. As seen in Figure 1, this portion of the lubricator is disposed immediately under the lowermost portion of the journal, and immediately above the bottom or lowest portion of the journal box. The capillary carriers 26 of these portions of the blankets 14 lie along a substantially straight line and extend from a position adjacent the lowest portion of the journal box to a position adjacent the lowest portion of the journal. This arrangement provides wick means extending through the center of the packing resulting in an unusually short feed path from the oil reservoir of the journal box to the journal and tests have shown that this center feed arrangement permits lubricant to reach the journal six to seven times faster than in conventional packings wherein the envelope is looped around a single core.

This provision of a short center feed together with the addition of a second woven carrier in each blanket 14 provides a substantial increase in the oil film applied to the journal and substantially reduces the time required after long periods of inaction for adequate lubrication of the journal. Even when the packing shifts to the right or left of Figure 1, the feed path remains relatively short. It should also be noted that this center feed feature is obtained by me without sacrificing other advantageous features of the invention, such as installation without jacking the box.

Additionally, the longitudinally extending stitching 41 shown in Figure 11 and the adhesive layer 29 of each blanket make the individual fibers of the blanket fast to the lubricator, thus precluding the possibility of a "hot-box." It will also be observed that by forming the blanket 14 so that the waste threads extend transversely of the journal and longitudinally of carriers 26, the waste threads tend to supplement the capillary lifting action of the carriers 26.

The configuration of the packing 12 is particularly adapted to prevent draining of lubrication oil out of the rear end of the journal box. As seen in Figure 5, the

notches or indentations 34 of the rear edges 33 of the blankets 14 combine to provide an indentation or re-entrant angle 80 in the rear of the lubricator which forms a drain port outwardly of the rear fillet of the journal and permits the excess oil accumulating between the two lubricating bodies formed by the blankets 14 and their respective core means during operation of the journal to drain back to the oil reservoir of the journal box. This prevents the rear portion of the journal from forming with the packing sort of a "pitcher spout" which acts to pour the excess oil out of the rear of the journal box.

Also, oil tends to return to the oil reservoir through the central packing hole formed by the perforations 38 of blankets 14.

As seen in Figure 1, the outwardly extending edges of the packing have a "peaked" or tent-like configuration forming shelf means or wing-like projections that tend to catch a good portion of the surplus oil which drips from the bearing during operation, thereby saturating the area of each blanket 14 at the juncture of the respective blankets and the journal surfaces. This permits a heavier film of oil to be applied to the journal during operation. Excess oil collecting at this portion of the packing drains back to the oil reservoir through the hollow rivets 74 at the rear ends thereof. However, it will be noted that the coating 29 on the inner face of the blanket acts as a barrier or oil flow inhibitor to prevent drainage from the shelf means to the oil cellar through the contiguous lower flap or wall of the lobe blanket.

The semi-circular notches or cutout portions 36 on the side edges of the packing not only aid in making the packing more flexible but also permit installation in bolted boxes having internal bosses. These cutout portions not only permit the packing to clear these bosses, but also help to prevent it from shifting toward the front of the box, since the cutout portions will be received about the bosses.

The harness straps 22 and 22a are particularly designed to hold the core means of each blanket very securely. In straps 22, trapezoidal flap 68 of the rear tapes 60 covers the inside corner of the individual resilient pads 20, and the supplemental straps 66 secured to the front of each blanket prevents the pads from shifting to the rear of the packing, especially during installation. Straps 22a are also formed with a flap 68 that performs the same function.

As seen in Figures 6 and 16, the central surfaces of upper and lower pairs of resilient pads 20, which face each other, are somewhat shorter in total length than the surfaces that face outwardly of the lubricator (though only the top pads are shown in, for instance, Figure 6, it is to be understood that the bottom pads are similarly shaped). In the embodiment of Figure 6, the front and rear ends of the pads converge interiorly of the packing because of the manner in which the pad ends are trimmed. This arrangement provides space at each end of the packing into which the strap ends may be pressed, and by making the sides of the straps 22 that are adjacent the supplemental straps 66 shorter than the other sides, bulging of the harness strap ends when the packing is compressed is prevented. If the legs 59 were permitted to bulge, they would come into contact with the journal cellar at the front end of the box 10 and become pinched between the journal and the inside lower wall of the dust guard (not shown) in the rear, with resulting undesirable wearing of the lubricator. The arrangement of Figure 15 prevents bulging of the strap 22a outwardly of the lubricator as the ends of the core pads 20a form pockets in the legs of these straps and take up any looseness, and the centrally tapering ends of these pads provide plenty of room to accommodate bulging as the lubricator is compressed.

It will be observed that the package 12 is substantially symmetrical, and that when it is desirable to present a

new surface against the journal, the packing may be removed, turned over, and reinserted. Thus, the used surface of the blankets will be facing downwardly in the journal box and the hitherto unused waste surface of the blankets will be in contact with the journal. The package 12 is therefore a two-sided or reversible one with a corresponding increase in useful life. Moreover, by positioning the edges of the blanket at the sides of the packing, capillary action is just as good regardless of which side of the lubricator is in contact with the journal.

The positioning of the edges of the blankets at the sides of the packing also serves another important function in that the capillary feed path is broken at the sides of the packing. This inhibits return flow of lubricant to the cellar of the journal box during periods of inaction, and thereby insures more lubricant for immediate application to the journal when movement of the journal again begins.

During operation of the journal, the membrane-like barrier formed by the adhesive cooperates with the journal and the capillary material to provide a reflux type action on the oil that is applied to the journal. Assuming that the journal rotates clockwise in the showing of Figure 1, oil drips or is thrown by the journal back onto the upwardly projecting side of the underlying lobe of the lubricator; since the oil is retained adjacent the capillary material by the underlying membrane-like barrier, it is reapplied to the journal to supplement the oil reaching the journal by capillary action through the capillary material. As rotation continues, the oil film applied to the journal increases until a stabilized condition is arrived at. The wing-like projections formed by the sides of the lubricator provide positive oil deflectors that catch the oil and prevent it from moving into the space between the packing and the journal box housing side wall.

The handle means 16 makes it relatively easy to remove the package 12 from the journal. The metal or metallic end pieces 38 are formed with an opening adapted to receive a hook similar to that ordinarily found on a box packer's tool, and by which the package may be withdrawn from the journal box.

The stitching 46 illustrated in Figure 11, is particularly adapted to avoid constriction or confinement of the high capillary action material making up the woven carriers 26. It will be observed that instead of employing stitching that runs all the way across the blanket longitudinally of the lubricator, the individual stitchings 46 are spaced apart longitudinally of the packing and extend transversely thereof. This insures that there will be considerable portions of the woven carriers 26 that are not bound at all by the stitching 46. Also, stitchings 46 are preferably as loose as is permitted by the nature of my package.

The foregoing description and the drawings are given merely to explain and illustrate my invention and the invention is not to be limited thereto, except insofar as the appended claims are so limited, since those skilled in the art who have my disclosure before them will be able to make modifications and variations therein without departing from the scope of the invention.

I claim:

1. A journal box packing comprising a waste blanket of generally quadrilateral configuration bent double to bring two opposite ends together whereby said blanket comprises a bent portion that is diametrically opposed to said opposite ends thereof, means securing said opposite ends of said blanket together with the edges thereof extending outwardly of the space enclosed by said blanket, a resilient core received in said space enclosed by the bent blanket, said core comprising a pair of superposed resilient pads extending lengthwise of the packing, and an H-shaped strap securing said pads to said blanket, with the web of said strap extending lengthwise of and between said pads and the legs of the strap being secured to the edges of said blanket, and with the ends of said pads being disposed

to the edges of said blanket, with the leg of the strap positioned at the rear of the packing substantially covering the rearwardly facing ends of said pads, and a supplementary strap secured to the portion of said rear leg that is adjacent said bent portion of said blanket, said supplementary strap being secured to the bent portion of said blanket.

2. The journal box packing set forth in claim 1 wherein the sides of said pads adjacent said bent portion of said blanket are shorter than the sides adjacent said opposite ends thereof, wherein the ends of said pads are disposed in planes that are inclined with respect to said bent portion of said blanket, and wherein the respective straps are provided with short sides corresponding with the shorter sides of the respective pads.

3. The journal box packing set forth in claim 1 wherein the sides of said pads adjacent the bent portion of said blanket are shorter than the sides adjacent said opposite ends thereof, and wherein the ends of said pads are disposed in planes that converge toward the center of the packing.

4. In a lubricator for a railroad car journal box of the type in which the floor of the box serves as an oil reservoir and oil is lifted by the lubricator to the under-surface of a car axle journal that extends into the box, and including a front end and a rear end adapted to be positioned adjacent the front and rear ends, respectively of the journal box, said lubricator comprising a pair of resilient core structures adapted to be compressed and inserted in side by side relationship between the axle journal and the floor of the box and parallel to the car journal, said core structures extending longitudinally of the lubricator, a fabric blanket secured about each of said core structures, said lubricator including side edges that are adapted to be respectively positioned adjacent the respective sides of the journal box, each of said blankets comprising a flexible sheet having its ends secured together along said side edges of the lubricator with an oil barrier interposed therebetween, said sheets including capillary means for lifting oil from the bottom of the oil reservoir to the journal, said capillary means comprising a multitude of continuous high lift capillary yarns extending transversely of the journal and contained in the portions of said sheets that are interposed between said core structures, said ends of the respective

blankets projecting outwardly of the lubricator toward the respective sides of the journal box when the lubricator is placed in the journal box, and forming shelf means adapted to catch oil drippage from the axle journal during rotation thereof for re-application to the journal, and means for securing said flexible sheets together between said core structures.

5. The lubricator set forth in claim 4 wherein said ends of said blankets are notched substantially midway along the side edges of the lubricator, said notches of said side edges being aligned transversely of the lubricator.

6. The lubricator set forth in claim 4 wherein said edges of said blankets are formed with oil drainage perforations adjacent the rear end of the lubricator whereby excess oil collecting on the respective shelf means drains back to the oil reservoir.

7. A journal box packing comprising a waste blanket of generally quadrilateral configuration bent double to bring two opposite ends together whereby said blanket comprises a bent portion that is diametrically opposed to said opposite ends thereof, means securing said opposite ends together with the edges thereof extending outwardly of the space enclosed by said blanket, a resilient core received in said space enclosed by said blanket, said core comprising a pair of superposed resilient pads extending lengthwise of the packing, and an H-shaped strap securing said pads to said blanket, with the web of said strap extending lengthwise of and between said pads and the legs of the strap being secured to the edges of said blanket, and with the ends of said pads being disposed

11

in planes that are inclined with respect to the plane of the packing and converge toward the center of the packing, said pads each being shorter than the length of said packing but being of sufficient length to bear firmly against the respective legs of said straps, whereby when the pads are compressed longitudinally of said legs of said straps, bulging of said legs outwardly of the blanket is prevented.

8. For use in a car journal in which an axle journal is supported within a journal box having an oil cellar at the bottom thereof, a lubricator adapted to be inserted in the box between the journal and the bottom of the box, and including side edges that are respectively adapted to be positioned adjacent the respective sides of the box, said lubricator comprising twin longitudinally extending lobes, each including continuous strands of capillary material adapted to feed oil to an applicator surface in the region of said journal, and resilient means adapted to urge the applicator surface into contact with the journal, said strands of each lobe extending from said applicator surface to substantially the bottom of the oil cellar along substantially the center line of the box when the lubricator is placed in said box, and being discontinuous along said side edges of the lubricator to inhibit return flow of oil to the cellar along the said edges of the lubricator, oil barrier means interposed in said side edges at said discontinuity of the strands and means for joining the two lobes together.

9. A center feed lubricator for use in journal boxes of the type in which an axle journal is supported in the box, with an oil cellar at the bottom of the box, said lubricator including side edges that are respectively adapted to be positioned adjacent the sides of the box, and comprising twin lobes extending longitudinally of the lubricator with at least the upper and adjacent margins of the lobes being formed of capillary material, and with the upper margin of the lobes constituting an applicator surface, said material including yarns that extend transversely of the lubricator, whereby oil may be fed from the lowermost part of the oil cellar to the said applicator surface of said capillary material when the lubricator is in place in said box, said yarns being interrupted along said side edges of the lubricator to inhibit return flow of oil along said edges of the lubricator, oil barrier means interposed in said side edges at said interruption of the strands resilient means in each of said lobes adapted to urge the applicator surface into contact with the journal, and means for securing the lobes together.

10. A center feed lubricator for use in journal boxes of the type in which an axle journal is supported in the box, with an oil cellar at the bottom of the box, said lubricator including side edges that are respectively adapted to be positioned adjacent the sides of the box, and comprising twin lobes extending longitudinally of the lubricator with at least the upper and adjacent margins of the lobes being formed of high capillary action material, and with the upper margins of the lobes constituting an applicator surface, said material including high lift yarns that extend transversely of the journal and into the cellar of the box when the lubricator is in place within said box, whereby oil may be fed from the lowermost part of the oil cellar to said applicator surface of said capillary material, said yarns being interrupted along said side edges of the lubricator to inhibit return flow of oil along said edges of the lubricator, resilient means in each of said lobes for urging the applicator surface into contact with the journal, means for securing the lobes together, and means associated with each lobe for retarding the drainage of excess oil from said surface of each lobe, the last mentioned means comprising oil barrier means interposed between said surface and said resilient means of each lobe.

11. In a lubricator for use in journal boxes of the type in which an axle journal is supported in the box, with an oil cellar at the bottom of the box, said lubricator in-

12

cluding side edges that are respectively adapted to be positioned adjacent the side edges of the box, and comprising a twin lobe body in which the lobes thereof extend longitudinally of the lubricator, said lobes each comprising a blanket having a foundation of capillary material including continuous high lift strands that extend transversely of the lubricator, resilient means in each of the lobes for urging the blanket into contact with the journal, said lubricator being formed with wing-like projections along said side edges thereof and said strands being discontinuous along said projections and oil barrier means interposed in said side edges of the lubricator at said discontinuity of the strands.

12. In a lubricator for use in journal boxes of the type in which an axle journal is supported in the box, with an oil cellar at the bottom of the box, said lubricator including side edges that are respectively adapted to be positioned adjacent the side edges of the box when the lubricator is received in the cellar thereof, said lubricator comprising a multi-lobe body, each of said lobes comprising a blanket of capillary material including high lift strands that extend transversely of the journal when the lubricator is in place within said box, and resilient means for urging said blankets into contact with the journal, said blanket of each lobe being formed into a pocket to receive the resilient means of each pocket, said body being formed with wing-like projections along said side edges thereof and said strands being discontinuous along said projections, oil barrier means interposed in said side edges at said discontinuity of the strands said lobes having symmetrically formed top and bottom applicator surfaces provided by said blankets, respectively, whereby the lubricator may be reversed to employ the underside thereof as the applicator surface of the lubricator.

13. The lubricator set forth in claim 9 wherein the undersurfaces of said blankets are provided with oil barrier means along said applicator surfaces of said lobes.

14. In a lubricator for a railroad car journal box of the type in which the floor of the box serves as an oil reservoir and oil is lifted by the lubricator to the undersurface of a car axle journal that extends into the box, said lubricator comprising a multi-lobe body, each of said lobes comprising a blanket of capillary material including high lift strands adapted to extend transversely of the journal, and resilient means for urging said blanket of the lobe into contact with the journal, said blankets of each lobe being formed into a pocket to receive the resilient means of each pocket, and means associated with each lobe for retarding the drainage of excess oil from the upper surface of the blanket of each lobe, the last mentioned means comprising oil barrier means interposed between said high lift strands and said resilient means of each lobe, said journal and said blanket during operation of the journal with the lubricator in place setting up a reflux action wherein oil is supplied to said surfaces from said reservoir by said strands and excess oil collects on said surface of each lobe and is re-applied to the journal to supplement the capillary feed of said strands.

15. In a lubricator for a railroad car journal box of the type in which the floor of the box serves as an oil reservoir and oil is lifted by the lubricator to the undersurface of a car axle journal that extends into the box, said journal extending between the axle collar and its rear fillet and said lubricator including a front end and a rear end adapted to be positioned adjacent the front and rear ends, respectively, of said journal, said lubricator comprising a resilient lubricating body adapted to be compressed and inserted between the axle journal and the floor of the box, said body being formed so that when said lubricator is in place in the box, the rear end of said body adjacent its sides contacts rear end of the box, but has its central portion spaced from the rear end of the box beneath said fillet, whereby an oil drain-

age passage is formed for return of oil to the oil reservoir.

16. The lubricator set forth in claim 15 wherein the rear end of said lubricator is indented to form said passage.

17. In a lubricator for a railroad car journal box of the type in which the floor of the box serves as an oil reservoir and oil is lifted by the lubricator to the under-surface of a car axle journal that extends into the box, said lubricator including side edges that are respectively adapted to be positioned adjacent the sides of the box, and comprising twin lobes extending longitudinally of the lubricator, said lobes each comprising a resilient core structure and a fabric blanket secured about said core structure, said blanket comprising a generally quadrilateral sheet looped about said core and having contiguous ends secured together with the inner surfaces of each end abutting each other and separated by oil barrier means, said ends of said blankets of each lobe being disposed along said side edge of the lubricator, and means for joining said lobes together along the center of the lubricator, said ends of said blankets forming relatively stiff and pointed roll preventing wings adapted to bear against the sides of the box and simultaneously provide a flared upper surface along each side edge of the lubricator for catching excess oil drippage from the journal.

18. In a lubricator for a railroad car journal box of the type in which the floor of the box serves as an oil reservoir and oil is lifted by the lubricator to the under-surface of a car axle journal that extends into the box, said lubricator comprising a multi-lobe body, each of said lobes comprising a blanket of capillary material including high lift strands adapted to extend transversely of the journal, and resilient means for urging said blanket of the lobe into contact with the journal, said blankets of each lobe being formed into a pocket to receive the resilient means of each lobe, said blankets being looped about said resilient means, respectively, to provide symmetrical formed top and bottom applicator surfaces to which oil is adapted to be fed from the oil reservoir by said high lift strands, whereby the lubricator may be reversed to apply either of said surfaces to the journal, and means associated with each lobe for retarding the drainage of excess oil from said surfaces of the lubricator when same are applied to the journal, said means comprising oil barrier means interposed between said high lift strands and said resilient means of each lobe along the top and bottom of the lubricator.

19. A journal box packing comprising a pair of fabric blankets of generally quadrilateral configuration, each of said blankets being bent double to bring two opposed edges together with the inner surfaces of each of said edges of the respective blankets abutting each other,

means for securing said edges of the respective blankets in said abutting relationship, whereby each blanket comprises a bent portion that is diametrically opposed to said opposite edges thereof, and said opposed edges of each blanket extend outwardly of the space enclosed by the respective blankets, said blankets each having parallel continuous strands of capillary material extending transversely of said opposed edges of the blankets, resilient means received in each of said spaces for distending the respective blankets, and means for securing said bent portions of said blankets together without impairing the capillary properties of said strands.

20. The packing set forth in claim 19 wherein the means for securing said bent portions of said blankets together comprises spaced stitchings, said stitchings extending transversely of said opposed edges and being spaced from each other by unstitched areas of the blankets.

21. In a lubricator for use in journal boxes of the type in which an axle journal is supported in the box, with an oil cellar at the bottom of the box, said lubricator comprising a multi-lobe body in which the lobes extend longitudinally of the body, said body being formed to extend longitudinally of the journal when said lubricator is inserted in the box, said lobes comprising spaced, substantially parallel, resilient cores and capillary blanket means enclosing said cores, said blanket means including high lift strands that are oriented to extend transversely of the journal when the lubricator is inserted in the box, 30 said blanket means comprising blankets defining spaced pockets into which said cores are respectively received, said body being formed with wing-like projections along the side edges thereof that are respectively adapted to be positioned along the side edges of the box when the lubricator is inserted in the box, said strands being discontinuous along said projections, and oil barrier means interposed in said side edges in the region of said discontinuities of the strands.
